UNITED STATES PATENT OFFICE.

EDWARD B. NELSON, OF CADIZ, OHIO, ASSIGNOR TO ROBERT P. SCOTT, OF SAME PLACE.

GARMENT-FASTENER.

SPECIFICATION forming part of Letters Patent No. 615,361, dated December 6, 1898.

Application filed January 31, 1898. Serial No. 668,669. (No model.)

To all whom it may concern:

Be it known that I, EDWARD B. NELSON, a citizen of the United States, residing at Cadiz, in the county of Harrison and State of Ohio, have invented certain new and useful Improvements in Garment-Fasteners; and I do hereby declare the following to be a full, clear, and exact description of the invention, such as will enable others skilled in the art to 10 which it appertains to make and use the same.

My invention relates to improvements in fasteners for ladies' dresses, its object being to provide a simple and effective device adapted to serve the combined purposes of a dress-skirt fastener and placket-closer and waist and belt retainer.

To the accomplishment of this end my invention consists in certain novel features of construction, combination, and arrangement 20 of parts, as will be hereinafter more fully described, and particularly pointed out in the appended claims.

In the accompanying drawings, forming part of this specification, Figure 1 is a vertical sectional view through the waistbands of a dress-skirt and waist, showing my invention applied thereto. Fig. 2 is a horizontal sectional view of same. Fig. 3 is an inner side view showing the meeting ends of a 30 skirt-waistband connected by the fastener. Figs. 4 and 5 are detail perspective views of the fastener members. Fig. 6 is a perspective view of a modified form of hook-plate.

Referring now more particularly to the drawings, 1 represents a dress-skirt having the waistband 2, 3 a waist or basque, and 4 a belt such as is ordinarily worn about the waist to conceal the meeting edges of the waist and basque. The skirt is provided, as 40 usual, with a placket-opening 4^a, which is adapted to be closed when the terminal ends 2^a 2^b of the waistband 2 are brought together and connected.

The improved fastener consists of two members, a retaining-plate 5 and a connecting-plate 6, said plates being preferably formed of spring metal slightly bowed or curved to conform to the contour of the waist and provided, respectively, with holes 7 7^a for passage of threads, whereby they are secured to 50 the opposite ends of the skirt-waistband 2,

as clearly shown in Fig. 3. The plate 5 is formed with a series of vertical locking-slots 8 and at its outer end with an integral guide-ear 9, depending from the upper edge thereof, 55 said ear having an inwardly-projecting lip 9^a for a purpose presently described. The plate 6 is provided at its outer end with an upwardly-projecting outwardly-curved arm 10, having two inturned end hooks 11 and an 60 outturned central hook 12 formed integrally therewith. The plate is also provided with a tongue or hook 13, which is adapted to engage either one of the locking-slots in the retaining-plate 5 to hold the two plates connected, and with a longitudinal slot 14. When the plates are connected, as shown in Fig. 3, the ear 9 overhangs and extends down on the inner side of plate 6 and its lip 9^a projects into the said slot 14 and serves as a guide and 70 stop to maintain the plates in alinement.

In operation the two fastening-plates are connected by engaging the tongue 13 of the plate 6 with one of the slots 8 of the plate 5, according to the size of the waist of the 75 wearer, the plate 6 sliding on plate 5 during this operation and being guided by the ear 9 and its lip 9^a, which prevent said plate from moving inwardly and upwardly. To the back of the waist, adjacent its lower edge, is attached, by sewing or otherwise, a plate 15, which is then engaged with the hooks 11 and the retaining central hook or ear 12 fitted over the upper edge of the belt 4. When this is 80 done, it will be seen that the skirt 1 is fastened 85 and supported, the placket-opening 4^a held closed, and the lower end of the waist and belt prevented from slipping out of place and leaving the meeting ends or edges of the two garment members exposed.

In Fig. 6 the plate 6 is modified in construction by dispensing with hooks 11, which retain the end of the waist in place.

It will be understood that changes in the form, proportion, and minor details of construction of the fastener may be made within the scope of the invention without departing from the spirit or sacrificing any of the advantages thereof.

Having thus fully described my invention, 100 what I claim as new and useful, and desire to secure by Letters Patent, is—

1. The combination with the waistband of a dress-skirt, of a fastener comprising two members attached to opposite ends of the waistband, one of said members having a series of locking-slots and a guide-ear, and the other member provided with a tongue to engage said slots and a hook to engage the upper edge of a belt, and said plates being provided with means for maintaining them in alinement with each other, substantially as described.

2. A garment-fastener, consisting of a retaining-plate provided with locking-slots and a guide-ear, and a connecting-plate having a tongue to engage said slots and an upwardly-projecting arm formed with integral inturned waist-retaining hooks and an outturned belt-retaining hook, and said plates being pro-

vided with means for maintaining them in alinement with each other, substantially as described.

3. A garment-fastener, consisting of a retaining-plate provided with locking-slots and a guide-ear having a projecting lip, and a connecting-plate having a longitudinal guide-slot to receive said lip, a tongue to engage said locking-slots, and an upwardly-projecting arm formed with integral inturned waist-retaining hooks and an outturned belt-retaining hook, substantially as described.

In testimony whereof I affix my signature in presence of two witnesses.

EDWARD B. NELSON.
